(57) **CLAIM**

The ornamental design for a wrench and socket assembly as shown and described.

DESCRIPTION

FIG. 1 is a perspective view of a wrench and socket assembly, showing the design;
FIG. 2 is a top elevation view of the wrench and socket assembly of FIG. 1;
FIG. 3 is a bottom elevation view of the wrench and socket assembly of FIG. 1;
FIG. 4 is a front elevation view of the wrench and socket assembly of FIG. 1;
FIG. 5 is a rear elevation view of the wrench and socket assembly of FIG. 1;
FIG. 6 is left side elevation view of the wrench and socket assembly of FIG. 1; and,
FIG. 7 is a right side view of the wrench and socket assembly of FIG. 1.
The dashed lines in the figures form no part of the claimed design.
